(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a rear view thereof;

FIG. 8 is a rear perspective view thereof;

FIG. 9 is a bottom view shown with the stand removed; and,

FIG. 10 is a section view taken along line 10-10 of FIG. 3.

The dashed broken lines are for the purpose of illustrating portions of the electronic device and form no part of the claimed design.

The closely spaced parallel diagonal shade lines on FIGS. 1-2 indicate translucency.

The relatively light gray shade lines on FIGS. 3-9 indicate contour and not surface decoration.
